UNITED STATES PATENT OFFICE.

GEORGE T. KEIL, OF WASHINGTON, DISTRICT OF COLUMBIA.

CLOCK STRIKING MECHANISM.

SPECIFICATION forming part of Letters Patent No. 429,455, dated June 3, 1890.

Application filed September 4, 1889. Serial No. 322,953. (No model.)

To all whom it may concern:

Be it known that I, GEORGE T. KEIL, a citizen of the German Empire, residing at Washington, in the District of Columbia, have invented certain new and useful Improvements in Striking Attachments for Clocks; and I do hereby declare the following to be a full, clear, and exact description of the invention, such as will enable others skilled in the art to which it appertains to make and use the same.

My invention relates to certain improvements in striking attachments for clocks, in which the starting, striking, and stopping arms are operated by a vertically-reciprocating spring-actuated post carrying a reciprocating sleeve; and the objects of the improvement are, first, to provide a device that shall be simple in construction, effective in operation, and which can be readily attached to any striking clock mechanism; second, to reduce the friction of the several arms to a minimum degree, and, third, to provide means whereby the attachment may be readily and quickly detached for repairs without removing either the face or back plate of the frame supporting the clock mechanism. I attain these objects by the mechanism illustrated in the accompanying drawings, in which—

Figure 1 represents a front elevation of a part of the ordinary clock mechanism, with the face-plate removed, showing my improvement connected therewith. Fig. 2 is a vertical sectional view taken on line $\alpha\alpha$ of Fig. 1. Fig. 3 is a rear elevation with a portion of the back plate broken away to show the pivoted foot of the reciprocating post. Fig. 4 is a perspective view of my improvement detached. Fig. 5 is a vertical sectional view of the same. Fig. 6 is a detail view showing the slotted 30 guide-plate within which the stopping-arm operates. Fig. 7 is a detail perspective view of one of the journal-bearings of the reciprocating post.

Similar letters refer to similar parts throughout the several views, in which—

The letter A indicates the face-plate and B the back plate of the frame supporting the clock mechanism.

C indicates the post carrying the hands, and 40 is provided at its rear end with pins c and c', arranged diametrically opposite each other.

D is the lock-wheel and E the starting-

wheel, both of which wheels are of the usual pattern, the wheel E being provided with a pin e, the purpose of which will presently appear.

F indicates the striker, which is secured to the shaft f, journaled in bearings made in the face and back plates, respectively, and is provided with an arm f, which engages the pins 55 g on the striking-wheel G, mounted on the shaft g'. A spring f² serves to return the striker to its normal position after the striking operation has been completed.

Journaled in bearings H and H', made in 65 the back plate of the frame, is a vertical post I, provided at its lower end with a pivoted foot-piece i, held in normal position by a spring i', one end of which is fastened to the foot i and the other or free end resting on 70 the post proper. A spring J surrounds the upper end of the post between the shoulder i² and the bearing H, and serves to return the post to its normal position after it has been raised by either the pin c or c'. Attached to 75 the post I, near its lower end, is an arm K, provided with a bent-up end k, which engages the pin e on the wheel E, for the purpose hereinafter explained.

A sleeve L, provided with an upper arm l 80 and a lower arm l', is mounted on the post I. The lower end of said sleeve is slotted at l², and the arm K extends through said slot about midway of its length, so that when the post I is being raised by either of the pins c 85 or c' the arm K will reach the upper end of the slot when the post has moved about half of the required distance, it being understood that the sleeve moves but one-half of the distance that the post moves. The arm l' extends beyond the shaft g², and is bent downward and provided with an inwardly-bent end l³, which engages successively the slots d in the stop-wheel D, and the arm l with a bent-up end l⁴, which engages the cam-shaped 90 slot m in a stop-plate wheel M. A guide-plate y serves to retain the arm l in proper position.

The bearing H' is slotted at its front end to allow the lower journal of the post to be 100 slipped in place after the upper journal has been inserted. A pin h serves to confine the journal in position.

The operation of the device is as follows:

Assuming the clock to be running, when the hour approaches one of the pins *c* or *c'* will be directly under the pivoted foot-piece of the post *I*, and as the minute-hand reaches 12 5 the pin *c* or *c'* will raise the post *I* and arm *K*, which is attached thereto. When the arm *K* reaches the upper end of the slot *l'*, the sleeve and its arms will be carried up with the post until the respective ends of said 10 arms are out of engagement with the cam-shaped slot in the stop-plate wheel *M* and the deep slot in the stop-wheel *D*. As soon as this is accomplished, the bent-up end of the arm *K* engages the pin *e* of the starting-wheel, 15 checks its movement for an instant, the pin *c* or *c'* passes the pivoted foot-piece, releasing the post, which is forced down to its normal position by the spring *J*, and the striking begins, during which operation the sleeve, by 20 the continued action of the pin *c* or *c'*, is caused to reciprocate vertically on the post until the end *l'* of the arm *l* drops into the next advancing deep slot *d* of the stop-wheel *D*, and the end *l'* of the arm *l'* drops into the 25 cam-shaped slot of the stop-plate wheel *M*.

If only the hour is required to be struck, but one pin *c* or *c'* will be required. When both are used, one is for striking the half-hour.

30 If at any time the clock should strike the wrong hour, all that is required to cause it to strike the right hour is to give the post carrying the hands a short turn to the left sufficient to allow one of the pins *c* or *c'* to pass 35 the pivoted foot-piece, the spring action permitting this to be done, and then a slight turn to the right, repeating the operation until the correct hour has been struck.

It will be observed that the device is so 40 constructed and arranged that it can be readily applied to the so-called "French clocks" by changing the position of the post *I* to the outside of the frame and slightly modifying the construction of *K l l'* and their relative 45 arrangement. In fact, it is applicable to almost every variety of clocks and to repeating-watches. It is easily applied or detached, requires no adjustment in applying it, and the cost is but small as compared with the old 50 cumbersome affair generally in use.

Having thus fully described my invention, what I claim as new, and desire to secure by Letters Patent, is—

1. The combination, with a clock mechanism, of a vertically-reciprocating spring-actuated post having an arm for engaging the starting-wheel and carrying a sleeve having an arm engaging the stop-plate wheel and an arm engaging the lock-wheel, substantially as 60 specified.

2. The combination, with a clock mechanism, of a vertically-reciprocating post journaled in suitable bearings and provided with an arm engaging the starting-wheel, a spring 65 for returning said post to its normal position, a sleeve mounted on said post and provided

with an upper arm engaging with the lock-plate wheel and a lower arm engaging the lock-wheel, and means for reciprocating the post, substantially as specified. 70

3. The combination, with a clock mechanism, of a vertically-reciprocating spring-actuated post carrying an arm for engaging the starting-wheel and provided with a spring-actuated pivoted foot-piece, a vertically-reciprocating sleeve mounted on the aforesaid post and carrying an arm engaging the lock-plate wheel and another arm engaging the lock-wheel, and means for reciprocating said post and sleeve, substantially as specified. 75 80

4. The combination, with the vertically-reciprocating post having an engaging-arm and a sleeve mounted on said post and carrying upper and lower arms, of the starting-wheel provided with a pin to engage the post-arm, 85 the stop-plate wheel provided with a cam-shaped slot to engage the upper sleeve-arm, the lock-wheel provided with slots for receiving the end of the lower sleeve-arm, and means for operating said post, substantially 90 as specified.

5. The combination, with the vertically-reciprocating post having an engaging-arm and provided with a pivoted spring-actuated foot-piece, and a sleeve mounted on said post and carrying an upper and a lower engaging-arm, of the starting-wheel provided with a pin for engaging the post-arm, the lock-plate wheel provided with a cam-shaped slot for engaging the upper sleeve-arm, the lock-wheel provided with slots to be engaged by the lower sleeve-arm, the post *C*, and pin *c* for reciprocating the post *I*, substantially as specified. 95 100

6. In a clock mechanism, the combination of the vertically-reciprocating post, its engaging-arms and pivoted foot-piece, the reciprocating sleeve and its engaging-arms, and means for reciprocating said post and sleeve, substantially as specified. 105

7. In a clock mechanism, the combination 110 of the vertically-reciprocating spring-actuated post provided with an arm to engage a pin on the starting-wheel and having a pivoted spring-actuated foot-piece, a sleeve mounted on said post, said sleeve slotted to receive the post-arm, and provided with an upper arm to engage a slotted stop-plate wheel and a lower arm to engage a slotted stop-wheel, and means for reciprocating said post and sleeve, substantially as specified. 115

8. The combination, with the mechanism of a clock, of the post *I i*, journaled in suitable bearings, the springs *J l'*, the arm *K l*, the sleeve *L l'*, carrying the arms *l l' l l'*, the guide *y*, the post *C*, and pins *c* and *c'*, substantially 120 125 as specified.

In testimony whereof I affix my signature in presence of two witnesses.

GEORGE T. KEIL.
